No. 36,374.

Patented June 23, 1903.

UNITED STATES PATENT OFFICE.

ERNEST GOTHLBERG, OF JERSEY CITY, NEW JERSEY.

DESIGN FOR A CHANDELIER-TRIMMING.

SPECIFICATION forming part of Design No. 36,374, dated June 23, 1903.

Application filed April 30, 1903. Serial No. 155,088. Term of patent 3½ years.

To all whom it may concern:

Be it known that I, ERNEST GOTHLBERG, of Jersey City, in the county of Hudson and State of New Jersey, have invented and produced 5 a new, original, and ornamental Design for Chandelier-Trimmings, of which the following is a specification.

The nature of my design is fully represented in the accompanying drawings, to which reference is made, and in which—

I claim as my invention—

The ornamental design for a chandelier-trimming, substantially as shown.

In testimony that I claim the foregoing as my invention I have signed my name in presence of two subscribing witnesses.

ERNEST GOTHLBERG.

Witnesses:

JOSEPH H. NILES,
HENRY J. SUHRBIER.
